(57) **CLAIM**

The ornamental design for a toe valgus orthotic device, as shown and described.

DESCRIPTION

FIG. 1 is a front and top perspective view of a toe valgus orthotic device design showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear and bottom perspective view thereof; and, FIG. 9 is a detail view of the toe valgus orthotic device identified in FIG. 1, shown enlarged for clarity of disclosure. The broken lines in the drawings depict portions of the toe valgus orthotic device that form no part of the claimed design.

1 Claim, 9 Drawing Sheets
